DISPENSER HAVING BRUSH OPERATED MEANS FOR RECIPROCATING THE SUPPLY CONTAINER AND LOOSENING THE MATERIAL CONTAINED THEREIN

William V. Eaton, Cleveland, Ohio

Application November 14, 1949, Serial No. 127,145

8 Claims. (Cl. 222—127)

1

This invention relates to dispensing devices, and more particularly to devices for dispensing fine granular or pulverized materials.

Materials in finely granulated or pulverized form, such as toothpowder, are generally packaged in containers. Then in order to use the toothpowder it is necessary to rotate a cap closing an opening or to remove the cap entirely, and then shake the container. Then, depending upon the vigor with which the container is shaken, quantities of the toothpowder will be ejected or caused to flow out. The quantities generally are limited since the toothpowder tends to "pack" in the narrow outlet opening. Means have been proposed for dispensing pulverized material in which a container can be positioned and vibrated, or lifted and dropped, so as to loosen the toothpowder. Generally such means are of an impact type, designed to jar some of the powder loose. Still other means have been proposed having a screw type powder material loosening device which upon rotation and when embedded in the powder will loosen and cause it to flow. These devices are generally intricate and expensive, and permit an accumulation of powder in their base wherein the actuating mechanism is located not infrequently causing a failure of operation, and making necessary an occasional disassembly for cleaning purposes.

This invention advantageously provides for a simple and an efficient device having a minimum of working parts that is adapted to dispense finely pulverized or granulated materials such as toothpowder. The dispensing device is adapted to readily measure out a desired quantity of the material onto a receptacle such as a toothbrush. Furthermore the device is adapted to be readily cleaned of accumulations without disassembly, particularly of the powder loosening means. A further advantage is the adaptability of the device to be mounted wherever convenient. It is provided with a separable holding or mounting means which may be attached wherever desired, and the dispensing element can be easily removed therefrom for replacement or cleaning purposes.

The invention will be more specifically described in the following specification and the accompanying drawing where:

Figure 1 generally discloses, in perspective, the assembled dispensing device with a schematic showing of a toothpowder container and brush in position;

Figure 2 is a front elevation of the dispenser;

Figure 3 is a lateral cross-section of the device;

2

Figure 4 is a cross-section taken along lines 4—4 of Figure 3; and

Figure 5 represents the container reciprocating and powder loosening device of the dispenser.

Referring to the drawing there is shown in Figure 1 a dispenser 10 having a body portion tapered substantially toward its middle and a diverging portion having an opening 11 into which a device such as a toothbrush 12 can be inserted. The taper in the dispenser body 10 advantageously comprises a construction for the concentration of flow of loosened and liberated finely ground, powder-like, material directing its flow onto a receiving device, for instance, a toothbrush that may be positioned in the opening 11 directly below. The dispenser body 10 is adapted to have mounted thereon a toothpowder or pulverized material container 13 resting on a moveable circular holding and supporting section 14 resting on the surface 15 of the dispenser 10. The supply support 14 has an opening 25 having a diameter adapted to receive the neck of a container 13. The opening 25, then, in the lower section of the support 14 converges to form a hopper in the shape of an inverted truncated cone. The hopper is shown as being circular, however, where a spreading of powder is desired the hopper outlet can advantageously take the form of an ellipse. The exterior of the support 14 hopper section, however, although of a lesser diameter than the portion above the surface 15, is generally cylindrical. Further, the end of the container support 14 within the body of the dispenser 10 is advantageously rounded so that dispensable material within the hopper section can be substantially physically contacted by the material loosening actuator device 20 for an entire raising and lowering period of the support 14.

Within the dispenser body 10 there are provided recesses 18 adapted to receive the pivots 19 of the actuator device 20 that is adapted to raise and lower the support 14 and, of course, a powder supply that may be positioned within the support. The actuator 20 pivots about the shaft extensions 19. It has a depending section 21 which merges with a substantially horizontal section 22 that is vertically serrated, then a downwardly vertically depending section 23 with a lower enlarged portion 24. The actuator 20 is supported by the pivots 19 and by the enlarged portion 24 which rests on the base of the dispensing device body 10. The powder supply support 14 is adapted to rest very lightly on the top of the serrated section, which may be rounded, 55 of the actuator 20.

In operation, with a supply 13 of a pulverized material such as toothpowder in position on the support 14 a toothbrush 12 is inserted through the opening 11 thrust and then withdrawn against the section 24 of the actuator 20. The motion is limited since section 24 will abut the inner wall of the device 10. This movement effects a rotation of the actuator 20 about the pivot points 19 raising and lowering the support 14 and the powder supply 13. Simultaneously with the lifting and lowering, in a sawing manner, the serrated section 22 loosens the compacted and slightly bulged powder extending beyond the mouth of the conical hopper and with which it is in contact causing the powder to drop along either side of the serrations onto the toothbrush. The section 22 acts, generally, as a valve or stopper. If a single thrust does not provide a sufficiency of powder onto a toothbrush then the aforesaid operation is repeated until the desired quantity is obtained.

The dispenser body 10 is advantageously provided with a holder or support 16 which can be attached to a wall or other vertical surface by means of screws 17. While the holder 16 is permanently fixed the dispenser 10 can be readily removed therefrom for replacement or for cleaning purposes.

The dispenser 10 may be formed of any suitable material, such as plastic, wood, vitreous material, hard rubber, or of metal, as desired. It is simple and sturdy in construction. It contains but two moveable parts, the actuator 20 and the container support 14. While the actuator 20 is permanently located within the dispenser body 10 the entire device is of a construction that permits ready cleaning of the interior since there are no other parts to contend with. The powder supply support 14 is readily removable, and spilled and accumulated material can be taken out either through the opening 11 or the opening created by the removal of support 14. The dispenser body 10, because of its symmetry, is advantageously adapted to be molded in plastic. A single mold will suffice.

I claim:

1. A dispensing device comprising, a body, a support for substantially vertically reciprocably supporting material to be dispensed positioned in said body, said support being hollow so that said material is adapted to flow therethrough, and an actuatable means in contact with the discharge opening of said supply support upon movement being adapted to vertically reciprocate said supply support and simultaneously frictionally loosen the material in said support causing it to flow.

2. A dispensing device comprising, a body, a support for substantially vertically reciprocably supporting a material to be dispensed, an open hollow lower portion in said body into which said support extends and into which said material is adapted to flow, and an actuatable means positioned in said hollow lower portion and in substantial contact with said dispensable material being adapted upon movement to reciprocate said material and simultaneously loosen it through contact causing it to flow into said lower hollow portion.

3. A dispensing device comprising, a body having a lower hollow portion, an opening in the top of said body communicating with said lower portion, means in said opening adapted to receive a supply of material to be dispensed having a tapered outlet in the lower hollow portion, and

an actuatable means positioned in said body being in substantial contact with said tapered outlet, said actuatable means being lesser in size than said outlet opening so that when said latter means is actuated loosened material is adapted to flow about its sides.

4. A dispensing device comprising, a hollow body having an inward taper adapted to constrict flowing finely divided material and an opening in its top portion, a removable material container support in said opening and extending substantially into the tapered section of said hollow body, said support having an opening throughout its length for the flow of said material therethrough, said hollow body having an opening to the atmosphere in its lower section, a pivoted material loosening means in said hollow body being in substantial contact with said container support, said pivoted material loosening means being adapted upon actuation to raise and lower said container support, and said material loosening means being serrated along the length that is in substantial contact with said container support.

5. A dispensing device comprising, a hollow body having an inward taper in its sides adapted to constrict flowing finely divided material and an opening in its top portion, a removable material container support in said opening extending substantially into the tapered section of said hollow body, said support having an opening throughout its length for the flow of said material therethrough, said hollow body having an opening to the atmosphere in its lower section, a pivoted material loosening means in said hollow body being in substantial contact with said container support, said pivoted material loosening means being adapted upon actuation to raise and lower said container support, said material loosening means being serrated along the length that is in substantial contact with said container support, and said material loosening means having a depending vertical section for its actuation positioned in the lower portion of said hollow body and being accessible through said lower opening to the atmosphere.

6. A dispensing device comprising, a hollow body having an inward taper in its sides adapted to constrict flowing finely divided material and an opening in its top portion, a removable material container support in said opening extending substantially into the tapered section of said hollow body, said support having an opening throughout its length for the flow of said material therethrough, said hollow body having an opening to the atmosphere in its lower section, a pivoted material loosening means in said hollow body being in substantial contact with said container support, said pivoted material loosening means being adapted upon actuation to raise and lower said container support, said material loosening means being serrated along the length that is in substantial contact with said container support, and a removable supporting means for said hollow dispensing body.

7. A dispensing device comprising, a body having a vertical opening, a hopper positioned in said vertical opening, said hopper being adapted to support a supply of powder-like material, a pivoted means in said body adapted to raise and lower the hopper having a portion under said hopper in continuous substantial frictional contact during an actuation of said hopper, and said portion of said means in contact with said hop-

per having a lesser width than the outlet opening of said hopper.

8. A dispensing device comprising, a body, a vertical opening in said body, a hopper in said opening for supporting a powder-like material, said body having a hollow base, said hopper having an arcuate outlet to said hollow base, and means in said body positioned in substantial frictional contact with said hopper outlet for raising and lowering said hopper, the frictionally contacting portion of said means having an arcuate surface. 10
